UNITED STATES PATENT OFFICE.

WILLIAM M. SHEEHAN, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE STRUCTURE.

Application filed August 19, 1926. Serial No. 130,903.

My invention relates to railway rolling stock and consists in an improved construction of underframing for locomotives of the articulated type.

5 The main object of my invention is to provide an articulated underframe for a locomotive in which each of the articulated portions is an integral structure, preferably a one-piece casting, adapted to cooperate with 10 the other underframe unit in supporting the locomotive boiler and in transmitting the longitudinal stresses due to draft and buffing.

Additional object are to provide in such 15 underframe members interengaging load transferring elements at adjacent ends of the members, respective integral articulated joint elements, integral pedestals and transverse braces, integral bearings or other supports for the boiler and for the members of 20 the spring equalizing system.

I also desire to provide cast steel underframe members on which the steam cylinders may be directly mounted and which will 25 have integral portions forming parts of the steam passageways from the boiler to the cylinders.

I also desire in such production to provide 30 integral brackets for the application of brake cylinders, hangers, and levers, for the mounting of a cradle member and for mounting a front coupler or other draft transmitting device.

In the accompanying drawings which illustrate a selected embodiment of my invention—

Figure 1 is a side elevation of the two main units of my improved underframe assembled with each other and showing the 40 main elements of the locomotive superstructure in broken lines.

Figures 2 and 3, respectively, are top and side views of the front underframe member illustrated in Figure 1.

45 Figures 4 and 5 are similar views of the rear underframe member illustrated in Figure 1.

Figures 6, 7, and 8 are longitudinal vertical sections on lines 6—6, 7—7, and 8—8, 50 respectively, of Figure 2.

Figures 9 to 22, inclusive, are vertical transverse sections on lines 9—9, 10—10, etc. of Figure 3.

Figure 23 is a vertical longitudinal section taken on lines 23—23 of Figure 4. 55

Figures 24 to 30, inclusive, and Figures 33, 34, and 35, are vertical transverse sections taken on lines 24—24, 25—25, etc. of Figure 5.

Figures 31 and 32 are horizontal sections 60 taken on lines 31—31 and 32—32 of Figure 5.

I shall refer to the front underframe unit generally by the reference letter A and shall refer to the rear underframe unit generally by the reference letter B. Each of these units consists of a one-piece casting having spaced sides, the sides of unit A having recesses 1 for receiving the driver boxes (not shown) and at either side of these recesses the side portions 2 are substantially box-shaped in cross section to provide rigid pedestal and load transmitting sections. These sides are connected by transverse elements disposed both horizontally as indicated at 3 in various cross sections, and vertically as indicated at 4, these various transverse elements being provided with openings and recesses 5 for lightening the same for providing access to the space between the sides and for accommodating various items of equipment, such as piping, brake rigging, etc. 70

The unit is provided with an outwardly extending member 6 having upwardly facing bearings 7 adapted to slidably support 85 suitable brackets 8 mounted on the boiler C. Another transverse member 9 has its top face finished to provide a bearing for a similar bracket 10.

Between the recesses 1 in the sides of the 90 casting are located suitable fulcrums 11 on which the equalizers (not shown) are mounted and below these fulcrums are brackets 12 for mounting the brake hangers.

The lefthand end of unit A terminates in a bracket 13 upon which the buffer beam 14 and draft devices 15 may be mounted. Between brackets 13 and the nearest pedestal I provide a machined face 16 for mounting the steam cylinder (not shown) and the inner portion of the casting adjacent faces 16 are provided with suitable webs arranged to form steam passageways 17 leading to the cylinders. Transverse member 9, previously referred to, has an integral steam passage-way forming portion 18 terminating in in- 100 105

tegral flanges 19^a, and it will be understood that suitable piping (not shown) connects passageways 17 and 18.

The forward portion of unit A is also provided with a center pin guide 19 which serves as a bearing for a pivoted pony truck, the wheels of which are indicated at 20 in Figure 1. Suitable valve gear brackets 21 are provided on the sides of the frame adjacent to the cylinder mounting.

At the rear end of unit A I provide a centrally located rearwardly extending integral projecting tongue 22, forming a pivotal joint element which fits into the pocket 23 (see Figure 23) formed on the forward end of unit B and provided with suitable bosses 24 for receiving the pivot pin which assembles the two underframe units. Longitudinal stresses are transmitted through these elements. Vertical loads are passed from one unit to the other by means of the tongues 28 and recesses 39 which slidably interengage, permitting longitudinal and lateral movement of their contact surfaces.

The portion of unit B above pocket 23 forms a saddle 25 to which the boiler C is rigidly secured and near the rear end of unit B suitable brackets 26 are provided for the boiler supporting expansion plates 27 (see Figure 1). It will be understood that the rear end of the boiler is free to move longitudinally of underframe unit B but cannot move transversely of the same. The forward part of the boiler is free to move longitudinally and transversely of underframe unit A. This mounting of the boiler takes care of the relative movement between the boiler and the underframe units due to expansion and contraction and due to travel of the locomotive on curved track.

The boiler saddle 25 has an integral steam passageway 28 formed therein and other steam passageways such as 29 are provided in the casting and lead to the faces 30 on which the steam cylinders for the rear unit of the underframe are mounted.

The sides of unit B are provided with driving box recesses 31 and pedestal portions 32 similarly to the corresponding parts of the front unit A and the sides also have equalizer and brake rigging fulcrums 33 and 35, respectively, corresponding to fulcrums 11 and 12 in unit A.

The rear end of unit B terminates in brackets 36 to which the locomotive cradle 37 (see Figure 1) may be attached.

The structure described eliminates a large amount of the machining and assembling work required for the ordinary built-up structure and produces a two unit underframe of greater strength, for a given weight, than a built-up structure. The delays and expense, due to repairs, and other disadvantages of built-up structure are also avoided.

The details of my invention may be modified substantially without departing from the spirit thereof and I contemplate the exclusive use of such details as come within the scope of my claims.

I claim:

1. In an articulated locomotive, a cradle at one end, a draft element carrier at the other end, and two castings between and respectively mounting said cradle and carrier and forming the underframe for the locomotive.

2. In an articulated locomotive, a cradle at one end, a draft element carrier at the other end, and two castings between and respectively mounting said cradle and carrier, said castings being pivotally connected and forming the underframe for the locomotive.

3. In an articulated locomotive, a cradle at one end, a draft element carrier at the other end, two castings between and respectively mounting said cradle and carrier, said castings being pivotally connected and forming the underframe for the locomotive, and a boiler fixedly mounted to one of said castings and having sliding bearing on the other of said castings whereby the latter may swing relative to said boiler while supporting the same.

4. In an articulated locomotive, a cradle at one end, a draft element carrier at the end, two castings between and respectively mounting said cradle and carrier, said castings being pivotally connected and forming the underframe for the locomotive and mounting the boiler and steam cylinders and forming portions of the steam passageways between the boiler and steam cylinders.

5. In an articulated locomotive, an underframe consisting of a pair of cast frames provided with cooperating pivotal joint elements formed integrally with their respective frames.

6. In an articulated locomotive, an underframe consisting of a pair of cast frames pivotally assembled with each other and each comprising draft transmitting members formed integrally with the respective pivotal joint elements.

7. In an articulated locomotive, an underframe consisting of a pair of cast frames pivotally assembled with each other and each comprising draft transmitting members and pedestals formed integrally with the respective pivotal joint elements.

8. In an articulated locomotive, an underframe consisting of a pair of cast frames pivotally assembled with each other and each comprising draft transmitting members and pedestals and superstructure supporting elements formed integrally with the respective pivotal joint elements.

9. In an articulated locomotive, an underframe consisting of a pair of cast frames, one of which frames has an integral saddle

- adapted to fixedly mount a locomotive boiler and the other of which frames has integral elements forming sliding bearings for boiler supporting brackets.
5. 10. In an articulated locomotive, an underframe consisting of a pair of cast frames, there being integral steam cylinder mounting elements on the sides of one of said frames at the inner end thereof, a pivotal joint element between said cylinder mounting elements and formed integrally therewith and there being a cooperating pivotal joint element formed integrally with the other of said frames and projecting between said cylinder mounting elements.
10. 11. An underframe member for an articulated locomotive consisting of a one-piece casting having draft transmitting sides and integral outwardly extending brackets on said sides forming sliding bearings for boiler supporting brackets.
15. 12. An underframe member for an articulated locomotive consisting of a one-piece casting having spaced sides connected intermediate their ends by integral transverse members, there being a centrally located articulated joint element projecting beyond one of the ends of the underframe member and there being a centrally located draft bracket at the other end of the underframe member.
20. 13. An underframe member for an articulated locomotive consisting of a one-piece casting having spaced sides each having driving box recesses and portions intermediate said recesses forming pedestals, the outer ends of the end ones of said portions being connected by integral draft transmitting members, one of which members forms an articulated joint element.
25. 14. An underframe member for an articulated locomotive consisting of a one-piece casting having spaced sides connected by integral transverse members, one of which members forms a central bearing for a swiveling truck and another of which members forms a centrally located pivoted joint element.
30. 15. An underframe member for an articulated locomotive consisting of a one-piece casting with spaced sides each having portions forming driving box pedestals, the outer faces of one of said portions being adapted to mount steam cylinders for the forward driving unit of the locomotive.
35. 16. In an underframe member for an articulated locomotive consisting of a one-piece casting having draft transmitting sides with integral pedestals, steam cylinder mounting elements, and equalizer fulcrum brackets.
40. 17. In an underframe member for an articulated locomotive consisting of a one-piece casting having draft transmitting sides with integral pedestals, and brake
- hanger fulcrums and equalizer fulcrums formed integrally with said pedestals.
45. 18. A member for an articulated underframe for a locomotive, consisting of a one-piece casting with side frames adapted to mount steam cylinders, there being integral portions intermediate said side frames for bracing the latter and forming steam passageways.
50. 19. In an articulated locomotive, two underframe castings pivotally connected and having recesses and tongues respectively spaced from their longitudinal center lines and slidably interengaged to transfer vertical loads from one of said castings to the other.
55. 20. In an articulated locomotive, two underframe castings, one of said castings having an integral central projection at one end and having spaced recesses at the sides of said projection, and the other of said castings having a central recess for receiving said projection and having spaced tongues at the sides of said recess adapted to enter said spaced recesses on the other of said castings, said central projection and recess providing a pivotal connection for transferring longitudinal stresses and said spaced recesses and tongues providing interengaging elements for transferring vertical loads from either casting to the other.
60. 21. In a locomotive of the articulated type, two underframe castings pivotally connected to each other and a boiler fixedly mounted to one of said castings and having a movable bearing on the other of said castings whereby the latter may swing relative to said boiler while supporting the same.
65. 22. In a locomotive of the articulated type, combination of two main driving units, each comprising a plurality of axles; one of said units having mounted on its axles, a bed embodying a hinge tongue pocket; and the other unit, having mounted on its axles, a one piece casting comprising two main side frames, a plurality of cross tie members connecting the side frames, and a hinge tongue.
70. 23. In a locomotive of the articulated type, the combination of two main driving units, each comprising a plurality of axles; one of said units having mounted on its axles, a bed, embodying a hinge tongue pocket; and the other unit having mounted on its axles, a one piece casting, comprising two main side frames, a cylinder saddle, a hinge tongue and a plurality of cross tie members connecting the side frames.
75. 24. In a locomotive of the articulated type, the combination of two main driving units, each comprising a plurality of axles; one of said units having mounted on its axles, a bed, embodying a hinge tongue pocket; and the other unit embodying a hinge tongue and a one piece casting, comprising two main side frames, a plurality of cross tie members, con-

necting the frames, and a boiler saddle cross-bearer projecting laterally beyond the outer-sides of the frames.

25. In a locomotive of the articulated type, the combination of two main driving units, each comprising a plurality of axles, one of said units having mounted on its axles, a bed, embodying a hinge tongue pocket; and the other unit embodying a hinge tongue,

and a one piece casting, comprising two main side frames, a plurality of cross tie members connecting the side frames, a front frame, a boiler saddle crossbearer, and a cylinder saddle.

In testimony whereof I hereunto affix my signature this 12th day of August, 1926.

WILLIAM M. SHEEHAN.
